IRONING BOARD

William Frederick Tipping, Chislehurst, England, assignor to Simplus Products Limited, London, England, a British company

Filed Dec. 17, 1956, Ser. No. 628,896

8 Claims. (Cl. 38—135)

This invention relates to ironing boards.

It has been the common practice in ironing boards to provide a sleeve board which can be swung by a simple pivoting movement from a position underneath the main ironing surface to a position above the main ironing surface. Such arrangements, however, usually necessitates the sleeve board, when stored, being positioned well below the main ironing surface and it is an object of the present invention to provide an improved construction for supporting a movable sleeve board.

According to this invention, in an ironing board of the kind comprising a main board and a sleeve board, the sleeve board is slidably mounted underneath the main board for withdrawal in a direction transversely of the length of the main board.

It has previously been proposed to provide a sleeve board slidably mounted underneath one end of the main board for withdrawal in the longitudinal direction. By withdrawing the sleeve board transversely of the main board, the sleeve board may be much more firmly supported and the sleeve board may be provided with legs arranged so that, after the sleeve board has been withdrawn from underneath the main board, it can be supported above the level of the main board.

According to one feature of the invention, in an ironing board of the kind comprising a main board and a sleeve board, the sleeve board is supported on a pair of legs, each of which legs includes a rod-like portion extending transversely to the main ironing surface, underneath which surface this portion of the leg is pivotally mounted for rotation about its longitudinal axis, which portion is also slidably axially in its pivot mounting so that the sleeve board may be withdrawn outwardly to lie to one side of the main ironing surface. Each leg is shaped to have a U-shaped portion or is provided with a U-shaped clamp adapted to fit over the edge of the main ironing surface when the sleeve board legs have been swung about their pivots to the raised position and have then been moved inwardly. With this construction, assuming the sleeve board is in a raised position, it is then lowered by withdrawing it outwardly to disengage the U-shaped portion of the leg or the U-shaped clamp from the edge of the main ironing surface and then allowing the legs to rotate in their mountings until the sleeve board is beneath the level of the main ironing surface. The sleeve board may then be pushed underneath this main ironing surface by sliding the rod-like portions of the legs in their mountings.

The following is a description of one embodiment of the invention, reference being made to the accompanying drawings in which:

Figure 1 is a perspective view of an ironing board; and

Figure 2 is an underside perspective view of the ironing board of Figure 1 shown with the legs in the stowed position.

Referring to the drawings, there is shown a main ironing board 10 which is supported on a pair of pivotally

2

connected legs 11, 12. The legs 11, 12 are of tubular form and, where they are pivoted, are provided with flanged bushes 13 with the flanges providing enlarged bearing surfaces in the plane of relative movement, a pivot pin 14 being arranged to extend through the two bushes. At their lower ends the legs are secured to transverse bars 15 having rubber ferrules 16 forming feet. On the underside of the board 10 are secured two longitudinally extending angle members 17 having downwardly extending flanges 18. The leg 11 is secured to a cross member 20 which is pivotally mounted in the two flanges 18. The leg 12 at its upper end is secured to a tubular cross member 21 fitting between the flange 18 and inside which is an axially movable rod (not shown) having portions of such reduced diameter as to be capable of sliding along guide tracks 22 (Figure 1) which are formed as slots in downwardly extending portions 23 of the flanges 18. Each of the slots 22 is formed with a number of enlarged holes 24 and the axially movable rod in the tubular cross member 21 has enlarged portions which, by axial movement can be engaged in these holes 24 to prevent movement along the slot. This axially movable rod is preferably spring loaded so as to keep it in the locking position in which it engages in one of the holes 24 in each of the slots 22. This form of leg construction is described and claimed in co-pending U.S. application 628,893, now abandoned.

A sleeve board 30 is provided having two legs 31 formed of metal rod. Each leg is formed by a rod 30 which has a U-shaped portion 32 somewhere near the centre of its length and from the top of one arm 33 of the U the rod extends in a straight line in the plane of the U and at right angles to that arm of the U for a distance sufficient to position the sleeve board 30 at the required height above the main ironing surface, as shown in Figure 1. At the top end of this straight portion the rod is bent in another right angle to have an end portion 34 (Figure 2) lying in the plane of the U and extending parallel to the arms of the U in a direction toward the base thereof so that the end of the rod lies on or near an extension of the line of the base of the U. This end 34 of the rod fits slidably into a bush 35 or other bearing on the underside of the sleeve board 30. From the top of the second arm 36 of the U, the rod extends initially at right angles to that arm in a plane at an angle to the plane of the U so that the plane of the U can lie below the level of the end portion of the rod when the sleeve board is in the stowed position shown in Figure 2. From the end of this sloping portion 37 the rod extends at right angles in a direction parallel to the arms of the U and in a plane parallel to but above the plane of the U, this portion 38 extending in a direction opposite to the downward direction of the U. This last mentioned portion fits slidably in pivots in the aforementioned flanges 18. The sloping portions 37 of the rod shaped in this manner permit that, when the sleeve board 30 is in its lower position in which its underside rests on the arms 33, 36 of the U, the sleeve board is beneath the level of the main ironing surface 10 and hence can be slid underneath the main ironing surface when not in use (as shown in Figure 2). To raise the sleeve board from the position shown in Figure 2 to that shown in Figure 1 it is moved outwards by sliding the portions 38 in their pivots and is then swung upwardly, the portions 38 turning in their pivots. When in the raised position, the sleeve board is pushed inwardly so that the U-shaped portions 32 engage over the edge of the main ironing board 10.

In order to enable the whole surface of the board 10 to be used for ironing, there is provided an iron holder 40 which is more fully described and claimed in co-pending U.S. application No. 628,891, now abandoned.

On the opposite side of the board 10 to the iron holder is arranged a cord holder 47 which is more fully described and claimed in co-pending U.S. application No. 628,894, now Patent No. 2,923,077, granted February 2, 1960, and for supporting large articles, such as sheets, when they are being ironed, there is provided a work support 52.

As is described and claimed in co-pending U.S. application No. 628,895, now abandoned, the padding is secured on the main board 10 and the sleeve board 30 by means of canvas or like covers which fit over the tops of the boards and extend inwardly around the edges on the undersides of the boards as seen in Figure 2. At their inner edges 53 on the undersides of the boards, tension springs or elastic are provided in the covering material so as to retain the covers in position.

I claim:

1. In an ironing board having a main ironing surface, a sleeve board extending in the longitudinal direction of said main ironing surface and having a pair of similar legs spaced apart in that direction, each of which legs includes a rod-like end portion extending transversely to the main ironing surface which rod-like portion is pivotally mounted on the underside of said main ironing surface for rotation about the longitudinal axis of the rod-like end portion and is also slidably axially in its pivot mounting so that the sleeve board may be withdrawn outwardly from underneath the main ironing surface to lie to one side thereof, pivot means connecting the end of each leg remote from said rod-like portion to the underside of the sleeve board for pivotal movement about an axis parallel to said rod-like portion, U-shaped means on each of said legs having the arms of the U parallel to but displaced from the axis of said rod-like portion of the leg, the arms of the U being spaced apart sufficiently in the direction between the rod-like portion and the point of attachment of the leg to the sleeve board to fit over the edge of the main ironing board by sliding the rod-like portions inwardly from the edge of the main ironing surface after the sleeve board has been withdrawn from underneath that surface and raised by pivoting the rod-like portions in their mounts, and each leg being formed by a rod-like member with the U-shaped means constituted by a bight in the member.

2. An ironing board as claimed in claim 1 wherein said U-shaped means on each leg lies below the sleeve board to act as a stop limiting downward movement of the sleeve board as the rod-like end portions of the legs are rotated about their axes to swing the other ends of the legs downwardly.

3. An ironing board as claimed in claim 1 wherein each leg is so shaped that the arm of said U-shaped means engaging the upper side of the main ironing surface is dis-

placed from the plane defined by the pivot axis of said rod-like portion and the pivot axis of said pivot means connecting the leg to the sleeve board.

4. An ironing board comprising a main ironing surface, a sleeve board extending in the longitudinal direction of said main ironing surface and having a pair of similar legs spaced apart in that direction, each of which legs includes one end portion extending transversely to the main ironing surface and pivotally mounted on the underside of said main ironing surface for rotation about the longitudinal axis of said one end portion, each of said legs further having its other end pivotally secured to the underside of said sleeve board with the pivot axis parallel to the axis of said one end portion and the leg being shaped so that the pivot axes are displaced from one another, the two legs being spaced apart longitudinally of the main ironing surface to form a parallel motion linkage permitting the sleeve board to be raised and lowered, and means on said legs adapted to engage said main ironing surface to lock the sleeve board in the raised position.

5. An ironing board as claimed in claim 4 wherein said one end portion of each leg is slidably mounted in its pivot axis to permit of movement of the sleeve board transversely of the main ironing surface.

6. An ironing board as claimed in claim 5 wherein said one end portion of each leg is slidably mounted to permit of the sleeve board in its lowered position being slid underneath the main ironing surface.

7. An ironing board as claimed in claim 4 wherein said means on said legs adapted to engage said main ironing surface comprise a U-shaped portion on each leg to fit over the edge of said main ironing surface when the sleeve board and legs are slid inwardly in the raised position.

8. An ironing board as claimed in claim 4 wherein stop means are provided on each leg arranged to engage the underside of the sleeve board, as the latter is lowered, to limit the downward movement of the sleeve board.
